INKING DEVICE

Harold W. Clark, Alliance, Ohio, assignor to The McCaskey Register Company, Alliance, Ohio, a corporation of Ohio

Original application June 8, 1939, Serial No. 278,091. Divided and this application April 12, 1940, Serial No. 329,271

5 Claims. (Cl. 101—102)

The invention relates to cash registers and similar calculating machines, and the present application is a division of my co-pending application Serial Number 278,091, filed June 8, 1939, and relates more particularly to a novel type of inking device.

It is a very convenient and desirable feature for cash registers and similar machines to be provided with two paper strips for recording transactions upon the machine, one strip forming a record or detail strip which is automatically rewound within the machine so as to be normally inaccessible, the portion of the other strip upon which each transaction is printed being adapted to be torn or cut off after each transaction providing a receipt to be given to the customer.

Attempts have been made to provide paper equipment for producing the above results by passing two strips of paper one across the other at substantially right angles to printing position; and also to obtain the desired result by passing two superimposed strips of paper upward between the usual printing mechanism and the platen roll, but there are certain objections to such methods as they require more or less complicated mechanisms and in some cases result in a considerable waste of the paper.

An object of the present improvement is to provide a new and novel type of inking device especially adapted for use in a duplicate printing machine which overcomes the objections to the type of paper feeding and printing mechanism above referred to.

Another object is to provide an inking device which will operate effectively to ink type segments or sectors formed upon or rigidly attached to the bell cranks which operate the conventional type carriers.

A further object is to provide a substantially rectangular frame movable in unison with one of the type bars and carrying an ink ribbon having an area substantially equal to that of the type bars.

A still further object of the invention is to provide such a rectangular ink ribbon carrying frame having a lug operatively engaging one of the type bars.

Still another object is to provide such a rectangular frame resting by gravity and movable in unison with one of the type bars.

Another object is to provide such an ink ribbon frame curved to conform to the curvature of the type bars.

A further object is to provide pivotally mounted, curved arms and means for detachably

connecting the rectangular ink ribbon frame thereto.

The above objects together with others which will be apparent from the drawings and following description, or which may be later referred to, may be attained by constructing the improved inking device in the manner hereinafter described, and illustrated in the accompanying drawings, in which:

Figure 1 is a sectional view through the rear portion of a cash register embodying the invention;

Fig. 2, a fragmentary sectional elevation of the rear portion of the cash register;

Fig. 3, a fragmentary elevation viewed from the opposite side of the machine from Figs. 1 and 2, of the pawl and ratchet mechanism for rotating the platen for the duplicate printing mechanism;

Fig. 4, a detached perspective view of one of the type segments for the duplicate printing mechanism;

Fig. 5, an enlarged fragmentary sectional elevation taken transversely through the machine showing the bell cranks which position the conventional type carriers for printing and the type segments for the duplicate printing carried upon said bell cranks;

Fig. 6, a perspective view of the bracket carrying the printing ribbon which cooperates with the type segments, showing the printing ribbon carried thereby; and

Fig. 7, an elevation of the printing ribbon and removable frame by means of which it is attached to the bracket shown in Fig. 6.

Similar numerals refer to similar parts throughout the several views.

The invention is shown as applied to a "McCaskey" cash register of the general type disclosed in Johantgen Patents No. 1,306,112 and No. 1,336,840, the general calculating machine structure being substantially as shown in said patents, and therefore, the same will be described only briefly herein and only insofar as it relates to the duplicate printing mechanism to which the present application pertains, reference being made to said Johantgen patents for further disclosure thereof.

It should be understood that the disclosure herein is one embodiment of the invention which may be carried out in other forms and upon other well known types of calculating machines and that the invention is equally applicable to the hand operated type of cash register or the motor driven type of register in which a motor

key or bar is substituted for the hand lever to operate the main shaft of the machine to record each item or total of a transaction or a grand total of all transactions.

- 5 The machine illustrated is adapted to be controlled in customary manner by the usual depressible amount keys, not shown, by the operation of which the various items are set up in the machine in usual manner, the machine being 10 operated to print each item and enter it into the accumulating mechanism by operation of the hand lever or depression of the item key 11 as the case may be, all as in usual and well known practice.
- 15 As in usual practice, the main shaft, not shown, may be operated either by the usual hand lever or the usual motor key for operating the machine after the proper amount keys are depressed for each item to perform the usual adding and printing operations in usual and ordinary manner to record each item or total, as the case may be.

20 As is customary in machines of this type, the main shaft, not shown, may be operatively connected to the yoke 16, pivoted as at 18 upon a stationary part of the frame of the machine, such as the bracket 19.

25 Means not forming a part of this invention, and therefore not illustrated, may operatively connect the yoke 16 to the usual platen roll 24, so as to rotate said platen roll step by step in a counter-clockwise direction as viewed in Fig. 1.

30 A rocker arm 48 is fixed upon the rocker shaft 49, which is journaled transversely through the machine, and a spring 50 is connected to the stud 51 upon the free end of said rocker arm and to the yoke 16 at a point above and in rear of the pivotal point 18 thereof. A pull spring 52 is also connected to the stud 51 and to the base 53 of the machine.

35 The usual bell crank levers 54, common in machines of this type, are journaled upon the transverse shaft 55 in well known manner and a type carrier 56 provided with a type bar 57 is pivotally mounted upon each bell crank, as at 58, and the arms 59 of the bell cranks are pivotally connected as at 60 to the usual links 61 by means of which the bell cranks are operated in customary manner to properly position the type bars 57 in order to print upon the receipt strip 62 as it is moved 40 around the platen 24.

45 A segment 63 is fixed to or formed upon each bell crank 54 and extends rearwardly therefrom and is provided with an arcuate type bar 64 corresponding to the type bar 57 associated with the same bell crank 54 and so arranged that it will always assume the position relative to the platen 65 that the corresponding type bar 57 assumes relative to the platen 24.

50 The ribbon 66 is located between the type bars 64 and the platen 65, and is carried in a flexible frame 67 detachably connected to the curved arms 68 which are journaled upon the transverse shaft 55.

55 Means is provided for selectively positioning the ribbon carrying frame 67 so that different portions of the ribbon 66, from top to bottom thereof, are successively moved to printing position relative to the several type on each type bar, so that all portions of the rectangular ribbon are used to substantially the same extent.

60 This means may be controlled by the type bars themselves, and as shown in the drawings, the ribbon carrying frame is selectively moved by the type bar 64 for the tens of cents column. 65 In practice it has been found that in total op-

erations of a calculating machine the digits in this particular column are more uniformly distributed from 0 to 9 than in any other column, and since the duplicate printing mechanism to which this application pertains is shown as 5 adapted to print only the totals upon the record or detail strip, this particular type bar is selected to operate the movement of the printing ribbon.

60 For this purpose a lug 63a, upon the cross bar 10 68b, of the arms 68, rests upon the type bar 64 for the tens of cents column, so that the arms and frame 67 will move downward by gravity with said type bar, and will assume a selective printing position corresponding to the printing 15 position of said type bar.

65 As the particular type bar, which controls the movement of the ribbon 66, may be moved to any one of ten pre-determined positions with each operation, and as each of the other type 20 bars 64 may assume any one of ten different positions, it will be seen that due to this chance selection of printing location the entire area of the rectangular ribbon 66 will be substantially uniformly used for printing, thus permitting one 25 ribbon to be used for a considerable length of time before it becomes so badly worn that a good impression cannot be obtained.

70 For the purpose of easily attaching and detaching the ribbon, notches 69 may be formed 30 in the upper portion of the flexible frame 67 through which the attaching screws 70 may be located after the projections 71 at the lower end of the flexible frame are engaged under the lugs 72 upon the curved arms 68.

75 The rear platen 65 is carried in a U-shaped frame comprising the depending arms 73 and rigid cross bar 74, the arms being pivoted at their upper ends in the rear of the bar 74 to the frame as indicated at 75 so that the platen may 40 be swung toward or from the type bars 64.

80 One end of the shaft 76 of the platen 65 is extended into a block 77 which is pivoted as at 78 to the slotted plate 79 the other end of which plate is pivoted upon the stud 51 on the rocker 45 arm 48.

85 A cam slot 80 is formed in the plate 79 and receives the stud 81 upon the arm 82 of the yoke 16. This slot has a lug 83 projecting into its lower forward corner for a purpose to be 50 later described.

90 A backing up roller 84 is journaled upon a shaft 85 fixed to the lower ends of the links 86 which are pivoted at 75, and springs 87 between the links 86 and arms 73 of the U-shaped frame 55 normally hold the backing up roller 84 against the platen 65.

95 The stock roll for the record or detail strip may be placed within a suitable holder or container in the lower rear corner of the case 90 60 of the machine, the record strip 91 passing upward therefrom behind a bar 92 in the case located adjacent to the hinged door 93 on the back of the case by means of which access may be had to the record strip by an authorized person.

100 The record strip then passes over the roller or rod 94 then down between the backing up roll 84 and platen 65 and under and around said platen and then up and around the rewinding 70 spool 95 which has frictionally connected thereto a sprocket wheel, not shown, connected by sprocket chain 97 with a sprocket wheel, not shown, upon the shaft 23 of the conventional platen 24, whereby the rewind spool 95 will be 75

automatically operated by rotation of the platen 24 to rewind the record strip and keep the same under tension at all times.

5 A ratchet wheel 117 is fixed to the platen shaft 76 on the end thereof opposite to the block 77 and is engaged by a holding pawl 118 pivoted as at 119 upon the frame 31 and held in engagement with the ratchet 117 as by a spring 120.

10 An operating pawl 121 is pivoted intermediate its ends at 122 upon the frame 31 and held in operative position relative to the ratchet as by a spring 123.

15 In the operation of the machine, as each item is set up and recorded, the machine will operate in usual and well known manner to print the item only on the receipt strip 62 by means of the type bars 57.

20 For the purpose of causing the type 64 to print upon the record strip 91, means, disclosed in detail in my co-pending application, Serial No. 278,091, of which this is a division, may be provided for rotating the rocker shaft 49 forwardly, raising the rocker arm 48 and with it the adjacent end of the plate 79, locating the projection 83 in the slot 80 of said plate in the path of the stud 81 upon the arm 82 of the yoke 16, so that clockwise movement of said arm will engage the stud 81 with the projection 83, sliding the plate 79 forward, or to the right as viewed 25 in Fig. 2 and pulling the platen 65 against the type bars 64, so as to print the same total upon the record strip 91 which the type bars 57 print upon the receipt strip 62.

30 As the platen shaft 76 is pulled forward, a tooth of the ratchet wheel 117 thereon, as shown in Fig. 2, will ride over the operating pawl 121, and upon return movement of the platen shaft 76, the ratchet 117 will be rotated one tooth, so as to space the record strip 91 ready for the 35 next printing operation thereon.

40 I claim:

1. In a key-set calculating machine having independently movable type bars and an operating mechanism therefor and a platen adapted to receive the impressions of the selected type of the 45

type bars, a substantially rectangular frame movable in unison with one of said type bars and an ink ribbon carried by said frame and having an area substantially equal to that of the type bars.

5 2. In a key-set calculating machine having independently movable type bars and an operating mechanism therefor and a platen adapted to receive the impressions of the selected type of the type bars, a substantially rectangular frame 10 movable in unison with and having a lug operatively engaging one of said type bars, and an ink ribbon carried by said frame and having an area substantially equal to that of the type bars.

15 3. In a key-set calculating machine having independently movable type bars and an operating mechanism therefor and a platen adapted to receive the impressions of the selected type of the type bars, a substantially rectangular frame resting by gravity upon and movable in 20 unison with one of said type bars and an ink ribbon carried by said frame and having an area substantially equal to that of the type bars.

25 4. In a key-set calculating machine having independently movable curved type bars and an operating mechanism therefor and a platen adapted to receive the impressions of the selected type of the type bars, a substantially rectangular frame movable in unison with one of said type bars and curved to conform to the 30 curvature of said type bars, and an ink ribbon carried by said frame and having an area substantially equal to that of the type bars.

35 5. In a key-set calculating machine having independently movable type bars and an operating mechanism therefor and a platen adapted to receive the impressions of the selected type of the type bars, a substantially rectangular movable frame, an ink ribbon carried by said frame and having an area substantially equal to that of the type bars, and means for selectively moving the frame to a plurality of positions relative to the type bars.
